Primary Examiner — John Windmuller*Assistant Examiner* — John R Yeh(74) *Attorney, Agent, or Firm* — Mark D. Miller(57) **CLAIM**

We claim the ornamental design for a line clamp, as shown and described.

DESCRIPTION

FIG. 1 is a front perspective view of a line clamp showing our new design;

FIG. 2 is a different front perspective thereof;

FIG. 3 is a left side elevational view thereof;

FIG. 4 is a top plan view thereof;

FIG. 5 is a right side elevational view thereof;

FIG. 6 is a front elevational view thereof;

FIG. 7 is a bottom plan view thereof; and,

FIG. 8 is a rear elevational view thereof.
